UNITED STATES PATENT OFFICE.

WILLIAM A. GEIGER, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed April 3, 1924. Serial No. 703,842.

To all whom it may concern:

Be it known that I, WILLIAM A. GEIGER, a citizen of the United States, residing at Chicago, in the county of Cook and State of Illinois, have invented a certain new and useful Improvement in Hand Brakes for Railway Cars, of which the following is a full, clear, concise, and exact description, reference being had to the accompanying drawings, forming a part of this specification.

This invention relates to improvements in hand brakes for railway cars.

In the operation of hand brakes of the vertical staff type for railway cars, difficulty has been experienced heretofore due to the binding of the staff when released, this binding being frequently caused by the bulging of the end wall of the car or by bending of the staff itself, with the result that even though the brake is released in the usual manner, the chain will not become fully slack, thereby permitting the friction shoes to remain in contact with the wheels.

The object of my invention is to provide an arrangement especially adapted for hand brakes of the vertical staff type, wherein provision is made for positively insuring the full and free release of the brake staff so that the friction shoes may be freely disengaged from the wheels to minimize wear therebetween and reduce the tractive effort required of the locomotive.

Other objects and advantages of my invention will more clearly appear from the description and claims hereinafter following.

In the drawing forming a part of this specification, Figure 1 is a vertical sectional view taken through the end wall of a car and showing my improvements in connection therewith. Figure 2 is a horizontal sectional view of the structure illustrated in Figure 1 and corresponding to the section line 2—2 thereof. Figure 3 is a fragmentary vertical sectional view showing the manner of mounting the trip lever. And Figure 4 is a fragmentary horizontal sectional view through the supporting bracket, ratchet wheel and brake staff.

In said drawing, the end wall of the car is indicated at 10 and a housing or bearing bracket, designated generally by the reference character A, is secured thereto. Said bracket is provided with a rear wall 11 rigidly or otherwise secured to the car wall 10 by means of rivets 14, said bracket also

having a bottom web or wall 12 extending horizontally and provided with a journal bearing 13. An intermediate web or partition 15 extends horizontally from the rear wall 11 above the web 12 and vertical flanges 16 are provided to form an enclosing casing. A cap or cover plate 17 is also employed and is preferably connected to the main portion of the bracket casting A by means of the bolt 25.

A portion of the usual brake staff is indicated at 18, the same having its upper end 19 made square or of other non-circular cross section and on which is rigidly secured a ratchet wheel B. The ratchet wheel B is provided with an upper and a lower set of ratchet teeth 20 and 21 respectively, the lower end of the ratchet wheel being provided with a journal adapted to rotate within the bearing 13 of the bracket.

Oscillatably mounted on the ratchet wheel B is a carrier or fulcrum member, designated generally by the reference carrier C. Pivotally mounted on the fulcrum member is an operating handle or lever 22, said lever being pivotally connected to the carrier member by means of a horizontally extending pivot bolt 23. The handle 22 is provided with a spring-influenced pawl 24 adapted to cooperate with the set of ratchet teeth 20 of the ratchet wheel when it is desired to rotate the ratchet wheel in a chain-winding direction. In Figure 1, the operating handle is shown in inoperative position and when it is desired to rotate the ratchet wheel in a step-by-step movement to wind the brake chain on the staff 18, the operating handle is swung vertically to a horizontal position and then oscillated in the usual manner. After the handle is released, it automatically falls to a vertical, inoperative position as shown in Figure 1.

To hold the staff against accidental reverse rotation, I preferably employ the following means: A locking dog 26 having a toothed end 27 adapted to engage and coact with the ratchet teeth 21 is pivotally mounted on the vertically extending bolt 25, between the webs 12 and 15, the other end of the dog being extended to form a release handle or lever 28. A spring 29 is interposed between the toothed end of the dog and a stationary part of the bracket to normally urge the toothed end into cooperative engagement with the ratchet teeth 21. A sleeve or bush-

ing 30 is slidably mounted upon the vertical bolt 25 so as to be movable vertically thereon and is rigidly connected at its lower end to the dog 26 by means of a set screw 35 or 5 other suitable device, the upper end of said sleeve being provided with an annular enlargement or shoulder 31. A spring 32 is arranged between the cover plate 17 and the shoulder 31 to normally press the sleeve and 10 the dog carried thereby downwardly. The web portion 12 of the bracket is provided with fixed ratchet teeth 33, projecting above the upper face thereof and the dog is provided with ratchet teeth 34 on its under side, 15 said ratchet teeth being adapted to coact with the ratchet teeth 33, in a manner to be hereinafter described.

It is obvious that when the dog is in its normal position, as shown in Figures 1 and 20 2, the ratchet teeth 33 and 34 will be in mesh and the rotation of the ratchet wheel will cause the dog to oscillate about the pivot bolt 25 and permit of a step-by-step movement of said ratchet wheel, said dog riding 25 upwardly on the ratchet teeth 33 or lifting whenever the toothed end 27 is forced outwardly of the ratchet teeth 21, the oscillation of said dog, to permit of this step-by-step rotation of the ratchet wheel, being against 30 the pressure of the spring 32.

When the release handle 28 is pulled to the position indicated in dotted lines in Figure 4, it will retract the tooth 27 from the ratchet wheel, causing the ratchet teeth 35 34 of the dog to ride or lift relatively of the stationary ratchet teeth 33, advancing relatively thereto, and drop into re-engagement with the fixed ratchet teeth, so that after the release handle has been moved to 40 its released position, the dog will be held in its inoperative or retracted position out of engagement with the ratchet wheel.

In order to reset the dog to its normal position when it is desired to again wind 45 the ratchet wheel B, I have provided a trip lever 36 pivoted to the bracket at any suitable point as, for example, on the vertical wall 16 by means of a horizontal pivot bolt 37, the inner end of said trip lever being 50 forked as at 38 and engaging the under side of the shoulder 31. When it is desired to reset the dog to its normal operative position, the trip lever 36 is manually actuated and, as it pivots, its inner end will lift the 55 sleeve 30 and dog and permit the spring 29 to exert its force to oscillate the dog to its normal position.

The operation of the hand brake is as follows, assuming that the parts are in their 60 normal operative position as shown in Figures 1 and 2, with the dog tooth 27 coacting with the ratchet teeth 21 and permitting of a step-by-step winding movement of the ratchet wheel. In this position, the oscillation 65 of the dog necessary for the step-by-step

movement of the ratchet wheel will not be through an arc sufficient to cause the dog to ride completely over a ratchet tooth 33 and thus be held out of operative position by said ratchet teeth 33. When it is desired 70 to release the dog from its holding engagement with the ratchet wheel, the release handle is pulled horizontally to the position shown in dotted lines in Figure 4 and during the movement of the release handle, the 75 dog is oscillated sufficiently to cause it to ride or lift over the stationary ratchet teeth 33 and thence drop into reengagement therewith, to maintain the dog in its inoperative or retracted position to permit complete 80 release movement of the ratchet wheel. While the dog is held inoperative, the brake staff, even though it may stick or bind, during the latter portion of the release of 85 the brakes, will nevertheless be forced to continue its rotation in an unwinding direction when the car gets in motion and jarring of the brake chain occurs, thereby permitting the brake shoes to become fully 90 disengaged from the wheels and the brake chain to be fully slackened. When the operating handle 22 is to be again applied to wind the brake chain, the trip lever 36 is manually 95 actuated to lift the dog above the stationary ratchet teeth 33, whereupon the spring 29 actuates the dog forwardly into engagement with the ratchet wheel.

I have herein shown and described what I now consider the preferred manner of carrying out the invention, but the same is 100 merely illustrative, and I contemplate all changes and modifications that come within the scope of the claims appended hereto.

I claim:

1. In a hand brake for railway cars, the 105 combination with a vertical brake staff and a ratchet wheel rotatable in unison therewith; of means for rotating said staff in a step-by-step movement; a locking dog co-acting with said ratchet wheel to prevent 110 accidental reverse rotation thereof; means automatically operable to lock said dog in inoperative position when the latter is moved to said inoperative position, said means including an element operable to effect re-setting of said dog in normal position; and a lever pivoted about an axis at 115 an angle to the axis of said element and adapted to coact therewith to operate the same.

2. In a hand brake for railway cars, the 120 combination with a rotatable ratchet wheel; of means for rotating said wheel in a step-by-step movement in a winding direction; a release handle; a spring-influenced locking dog integral with said release handle and cooperating with said ratchet wheel to hold the same against accidental reverse rotation and actuated to inoperative position 125 by said release handle; means automatically 130

operative to lock said dog in released position out of engagement with said ratchet teeth when said release handle is moved to released position, said means being arranged to permit normal ratcheting of said dog prior to release; and means for releasing said automatic means to permit said dog to return to ratchet-engaging position.

3. In a hand brake for railway cars, the combination with a vertical staff and a ratchet wheel rotatable therewith; of means for rotating said wheel in a winding direction; a locking dog normally coacting with said wheel to prevent accidental reverse rotation thereof; a release handle operable to move said dog to inoperative position; means for locking said dog in inoperative position after its movement to inoperative position by said handle, said means comprising ratchet teeth carried by said dog independent of the wheel engaging portion coacting with stationary ratchet teeth on a fixed part of said brake, and a spring arranged to hold said last-mentioned ratchet teeth in mesh; and means for bodily shifting said dog to disengage said ratchet teeth.

4. In a hand brake for railway cars, the combination with a rotatable ratchet wheel; of means for rotating said wheel in a winding direction; a spring-pressed locking dog pivotally mounted to swing in a substantially horizontal plane and coacting with said ratchet wheel to prevent accidental reverse rotation thereof; a release handle operable to move said dog to inoperative position; means for automatically locking said dog after its actuation to inoperative position by said handle, said means being manually operable independently of said release handle to elevate said dog, said last-mentioned means including ratchet teeth carried by said dog and coacting with fixed ratchet teeth; and a spring arranged to hold said last-mentioned ratchet teeth in mesh.

5. In a hand brake for railway cars, the combination with a supporting bracket; of

a ratchet wheel rotatable thereon; means for rotating said wheel in a step-by-step movement in a winding direction; a spring-pressed, pivotally mounted locking dog coacting with said ratchet wheel to prevent reverse rotation thereof; a release handle for moving said dog to inoperative position; means for automatically locking said dog in inoperative position after said dog has been moved to inoperative position by said handle, said means comprising ratchet teeth carried by said dog, and ratchet teeth formed on a stationary part of said bracket and engageable with said last-mentioned ratchet teeth; a spring arranged to hold said last-mentioned ratchet teeth in mesh; and a manually engageable member operative to shift said dog in a direction independent of its pivotal movement out of mesh with said stationary ratchet teeth to permit it to reengage said ratchet wheel.

6. In a hand brake for railway cars, the combination with a rotatable member adapted to effect tightening of the brake chain when rotated in one direction and having a ratchet wheel rigidly associated therewith; means for effecting step-by-step rotation of said member in a chain-tightening direction; a locking dog co-operable with said ratchet wheel to prevent reverse rotation thereof, said dog being movable in one direction in its ratcheting action and adapted also for limited movement in a direction at an angle thereto; means for retracting said dog beyond its operative ratcheting position; means automatically operable to retain said dog in its retracted inoperative position when so positioned by said retracting means; and means for shifting said dog in said direction at an angle to its ratcheting movement to thereby release the dog and permit its re-engagement with the ratchet wheel.

In witness that I claim the foregoing I have hereunto subscribed my name this 1st day of April, 1924.

WILLIAM A. GEIGER.
